UNITED STATES PATENT OFFICE.

CLARENCE W. WHITE, OF NORTH BENNINGTON, VERMONT.

REFLECTOR.

1,149,237.

Specification of Letters Patent. Patented Aug. 10, 1915.

Application filed November 22, 1913. Serial No. 802,339.

To all whom it may concern:

Be it known that I, CLARENCE W. WHITE, a citizen of the United States, and a resident of North Bennington, in the county of 5 Bennington and State of Vermont, have invented certain new and useful Improvements in Reflectors, of which the following is a specification.

This invention relates to reflectors, more 10 particularly to reflectors for use with incandescent lamps, and the objects of the invention are to construct a reflector that is very strong and durable.

Further objects of the invention are to 15 provide a guard for the open end of the reflector that can be locked into position to prevent breaking or stealing of the lamp.

To the accomplishment of the above objects and to such others as may hereinafter 20 appear the invention comprises a reflector, having at its open end an outwardly extending shoulder at right angles to a downwardly extending flange having a beaded edge, and means for holding the outer edge 25 of a guard in position against said shoulder.

The invention also comprises means for removably locking the guard in the open end of the reflector.

Referring to the drawings: Figure 1 is a 30 side elevation of a reflector made in accordance with the invention secured to an ordinary incandescent lamp socket. Fig. 2 is a bottom view of Fig. 1. Fig. 3 is a view showing the reflector in section. Figs. 4 and 35 5 are detail views of the locking means for the guard.

In the drawing A designates an ordinary electric light socket having a circular rib B which is adapted to engage a corresponding 40 groove or recess C provided in a split ring D which is made of metal and adapted to be sprung into position on the socket A as clearly shown in Figs. 1 and 3. The lower portion of the split ring D is threaded and 45 adapted to engage a similarly threaded collar E secured to the top of the reflector F.

When the lamp G is screwed into position it will be seen that the reflector cannot be removed from the socket without first 50 removing the lamp, as the glass globe of the lamp is larger than the opening in the top of the reflector.

The reflector F is preferably made of aluminum, although if desired the same can 55 be made of any other suitable metal, that

can be spun into shape and formed at its open end with an outwardly extending shoulder H at right angles to a downwardly extending flange J, having a beaded or rolled edge K. This shaping of the open 60 end of the reflector by providing a shoulder having a beaded flange greatly strengthens the reflector, which is very desirable as reflectors of this type are put to very rough usage, and it is important that the reflector 65 retain its original shape to properly reflect the light.

The present method of shaping the open end of the reflector permits of a suitable guard or covering M being secured in the 70 offset portion of the end of the reflector so as not to interfere with the proper reflecting qualities of the reflector. In the drawing the guard or covering M is shown as a wire screen of very large mesh, the edges of 75 which are secured to a large wire ring N which fits in the offset portion of the reflector as clearly shown in the drawings. This guard or covering M prevents breaking 80 of the lamp G and when the guard M is locked in position in the end of the reflector also prevents the lamp being stolen, as the lamp cannot be removed without first removing the guard. In the present instance the guard is secured in position by means 85 of two projections or pins O secured to the flange J and also by means of a movable pin P secured to a flat spring Q as clearly shown in Fig. 4. In the present instance the locking of the guard M in the end of the 90 reflector is accomplished by locking the pin P which is provided with a slot R in which the bolt S of the lock T is adapted to engage as clearly shown in Figs. 1 and 5. Instead of providing a wire guard such as described for closing the end of the reflector, a piece of glass which may be colored, when 95 the same is to be used for photographic purposes, can be used and held or locked in position in the same manner. The off-set portion of the end of the reflector makes a light tight joint and when a red piece of glass is used for photographic purposes no white light will pass around the edge of the glass which is a very important feature of 100 this construction.

While the invention has been described with particular reference to the details of construction, the same is not to be considered as limited thereto, as many changes 110

can be made and still fall within the scope of the invention set forth in the following claims.

What I claim is:

- 5 1. A reflector comprising in combination a guard, the open end of the reflector having an outwardly extending shoulder at right angles to a downwardly extending flange, and means for removably holding the outer edge of said guard in position against said shoulder, said shoulder and said flange being arranged out of the path of the light reflected by said reflector.
- 10 2. A reflector comprising in combination a guard, the open end of the reflector having an outwardly extending shoulder at right

angles to a downwardly extending flange, and means for removably holding the outer end of said guard in position against said shoulder, and means for locking the outer edge of said guard in position against said shoulder, said shoulder and said flange being arranged out of the path of the light reflected by said reflector.

In testimony whereof I have signed this 25 specification in the presence of two subscribing witnesses.

CLARENCE W. WHITE.
